US00D530590S

(12) **United States Design Patent** (10) **Patent No.:** **US D530,590 S**
(45) **Date of Patent:** **** Oct. 24, 2006**

(54) **HANDLESET GRIP**

(75) Inventors: **Yos Singtoroj**, Anaheim, CA (US);
Jason D. Veltz, Laguna Hills, CA (US)

(73) Assignee: **Newfrey LLC**, Newark, DE (US)

(**) Term: **14 Years**

(21) Appl. No.: **29/211,996**

(22) Filed: **Aug. 25, 2004**

(51) **LOC (8) Cl.** **08-06**

(52) **U.S. Cl.** **D8/302**

(58) **Field of Classification Search** D8/300,
D8/302, 305, 307, 312, 308, 314-320, DIG. 1,
D8/DIG. 2, DIG. 3, 338, 499; D7/394; 402/61;
16/110.1; 312/234.1, 332.1

See application file for complete search history.

(57) **CLAIM**

The ornamental design for a handleset grip, as shown and described.

DESCRIPTION

FIG. 1 is a perspective view of the new design for a handleset grip;

FIG. 2 is a front elevational view of the new design for a handleset grip;

FIG. 3 is a top plan view of the new design for a handleset grip, the bottom plan view being the mirror image;

FIG. 4 is a right side elevational view of the new design for a handleset grip, the left side elevational view being a mirror image; and,

FIG. 5 is a back elevational view of the new design for a handleset grip.

The broken lines in the Figures are for illustrative purposes only and form no part of the claimed design.

1 Claim, 3 Drawing Sheets
